UNITED STATES PATENT OFFICE.

CICERO H. LA CROIX, OF BANNISTER, TEXAS.

PULLEY-BLOCK.

1,181,898.

Specification of Letters Patent.

Patented May 2, 1916.

Application filed October 21, 1915. Serial No. 57,146.

To all whom it may concern:

Be it known that I, CICERO H. LA CROIX, a citizen of the United States, residing at Bannister, in the county of San Augustine 5 and State of Texas, have invented a new and useful Pulley-Block, of which the following is a specification.

The device forming the subject matter of this application is a pulley block of the sort 10 used in logging operations and elsewhere.

The present invention aims to improve a pulley block of the type above described by providing the same with a U-shaped suspending member which, in its turn, is 15 equipped with a depending prong, adapted to engage a support, to the end that the pulley block may be sustained against vertical swinging movement.

It is within the province of the disclosure 20 to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood 25 that changes in the precise embodiment of the invention herein disclosed can be made 30 within the scope of what is claimed, without departing from the spirit of the invention.

In the accompanying drawing: Figure 1 35 shows the invention in side elevation, assembled with a post or support; Fig. 2 is a cross section on the line 2—2 of Fig. 1; Fig. 3 is a side elevation of the pulley block attachment forming, essentially, the subject 40 matter of this application; Fig. 4 is an elevation wherein the element shown in Fig. 3 is viewed at right angles to the showing of Fig. 3.

The device forming the subject matter of 45 this application is adapted to be used in connection with pulley blocks of widely different sorts and therefore, a specific and detailed description of a pulley block of any sort is unnecessary. Generally considered, the pulley block may embody plates

1 connected by an axle 2 on which is journaled a sheave 3. The plates 1 of the pulley block may terminate in ears 4 through which pass securing elements 5.

The invention comprises a U-shaped eye-forming member 6 embodying arms 7 and 8 terminated in thinned fins 9 received between the ears 4 and equipped with openings 10 adapted to receive the securing elements 5. Formed integrally with the arm 8 is a prong 11 terminated in a sharpened end 12. The prong 11 projects laterally from the arm 8 and is rearwardly extended, into approximate parallelism with the arm 8, the tip of the prong 11 being disposed beyond the bend 14 of the U-shaped member 6.

Through the eye forming member 6 is extended a binder 15 of any desired sort passed around a support 16 which may be a post, tree or stump, the extremity 12 of the prong 11 biting into one edge of the support 16 in a manner which will be clearly obvious from Figs. 1 and 2.

The cable which is threaded through the pulley block and engages the sheave 3 is denoted by the numeral 17. Owing to the provision of the prong 11, a vertical movement on the pulley block under the action of the cable 17 is avoided. Unnecessary wear is reduced, and the cable 17 will remain engaged with the tread of the sheave 3.

Having thus described the invention, what is claimed is:

1. The combination with a pulley block embodying a sheave, of an eye forming member assembled with the block and provided with a laterally projecting rearwardly extended support engaging prong disposed in a plane approximately at right angles to the plane of rotation of the sheave.

2. The combination with a pulley block embodying spaced plates and a sheave journaled therebetween, of a U-shaped member assembled with the plates and embodying arms one of which is provided with a laterally projecting rearwardly extended support-engaging prong disposed in a plane approximately at right angles to the plane of rotation of the sheave.

3. An article of manufacture adapted to

be employed in equipping a standard form of pulley block with a supporting strut, and comprising a U-shaped member including arms having terminal openings, one of the 5 arms being provided adjacent its opening with an outstanding prong prolonged in the direction substantially parallel to said arm.

In testimony that I claim the foregoing as my own, I have hereto affixed my signature in the presence of two witnesses.

CICERO H. LA CROIX.
